UNITED STATES PATENT OFFICE.

NATHANIEL B. WALES, OF NEW YORK, N. Y.

METHOD OF REFRIGERATION.

Application filed April 23, 1926. Serial No. 104,217.

This invention relates generally to refrigeration systems of the compression type and more particularly to new and improved means and a method of circulating the fluids used through the system.

It is a general object of the invention to provide a refrigeration system which will embody the advantages of both the flooded and the dry expansion systems without the usual limitations of either type.

A further object of the invention is to provide a refrigeration system which is especially adapted for long continued operation without service or attention.

An important feature of the invention is the provision of a high-speed compressor having a special construction designed to produce a high volumetric efficiency and handling without leakage, a brine-lubricant circulating liquid and a refrigerant of ammonia, propane or any other refrigerant having a relatively high vapor pressure.

In order to carry out my invention it is necessary to use a circulating fluid vehicle for the refrigerant which is a non-absorbent of the refrigerant and which possesses a substantially difference in specific gravity, preferably heavier, with relation to the refrigerant. This fluid vehicle or secondary fluid must also possess positive lubricating qualities and low freezing and light viscosity characteristics.

With these requirements in mind I have found that propane is well adapted for use as the refrigerating medium while ethylene glycol provides a satisfactory circulating liquid vehicle which I will hereinafter refer to as a "brine-lubricant". This chemical has approximately double the specific gravity of the refrigerant, has lubricating qualities, is non-absorbent and has relatively low freezing and viscosity characteristics.

Other features of the invention will be hereinafter referred to.

In the drawings in which a preferred embodiment of the invention has been selected for illustration,

Figure 1 is a view in vertical section of a refrigeration device embodying the invention.

Figure 2 is a diagrammatic view of the apparatus showing the path of movement of the circulating liquids.

Figure 3 is a view in vertical section and on an enlarged scale of a compressor unit forming part of the invention.

Figure 4 is a view in vertical section of the piston element used in the compressor.

Figure 5 is a face view of the disk valve element used in the compressor.

Referring to the drawings for a more detailed description of the invention, a refrigerating apparatus is shown in Figure 1 which includes a compressor 10, an operating motor 11, a condenser coil 12, and a vaporizing or refrigerating chamber 13.

The compressor 10 includes a piston 14 arranged to be reciprocated in a cylinder 15 through a pitman rod connection 16 with the driven shaft 17 which is rotated by the motor 11 at a relatively high speed approximating 1750 R. P. M. With this arrangement the velocity of travel of the piston exceeds the velocity imparted to the brine-lubricant by gravity and hence a film of brine-lubricant at all times covers the surface of the piston to simultaneously provide lubrication and a sealing action.

The cylinder 15 is mounted within a chamber 18 and is provided with two series of inlet ports 19 and 20, the lower ports 19 communicating with an annular space 21 surrounding the cylinder and having communication by way of the pipe 22 with the interior of the chamber 18 at a point above the brine-lubricant. The upper ports 20 communicate with an annular channel 23 surrounding the cylinder and having communication in turn through a port 24 with a sump 25 in which brine-lubricant 26 collects at the lower end of the chamber 18, a control member 27 can be adjusted to regulate the amount of liquid passing through the port 24.

The lower end of the cylinder 15 is normally closed by a disk valve member 28 against the lower surface of which a spring 29 supported by a closure cap 30 exerts pressure. An exhaust port 31 provides for the delivery of fluid from the compressor cylinder 15 to the condenser coil 12.

In order to reduce the relative back pressure on the up-stroke of the rapidly moving piston and, at the same time, facilitate the entrance of gaseous refrigerant into the space beneath the piston, a small valve 36 is mounted in the lower end of the piston in controlling relation to a passageway 37 leading downwardly therethrough. The valve opens on the up-stroke of the piston to permit gas to flow into the chamber 18 above the piston to the space beneath.

With this structural arrangement the up or suction stroke of the piston first uncovers the ports 19 whereupon gaseous refrigerant flows from the chamber 18 through the pipe 22 and channel 21 through the ports 19 into the cylinder 15 beneath the piston. A further upward movement of the piston uncovers the ports 20 whereupon a predetermined quantity of the brine-lubricant sufficient to fill the residual piston clearance space in the cylinder, enters the cylinder. On the down or compression stroke of the piston the refrigerant and a portion of the brine-lubricant drawn into the cylinder are forced by the valve 28 and through the exhaust ports 31 into the condenser coil 12.

The condenser coil 12, for the sake of compactness is placed in encircling relation to the horizontal compressor drive shaft 17 and the motor shaft 32. A flexible coupling 33 connects the two shafts and a fan 34 is mounted on the shaft 17 and rotated thereby to cool the windings of the condenser coil 12.

The helical turns of the condenser coil 12 are flattened in cross-section in order to provide an increased superficial area to aid in cooling and also to reduce the volume therein since the horizontal coil will have pools of liquid refrigerant formed in its convolutions with brine-lubricant at the lower portion of each convolution. Since the coils are flattened in cross-section, a slight increment in gaseous volume of the fluids flowing through the coil will carry forward the liquids settling in the base portion of the coils into a heat interchanger coil 35 and expansion valve 36 through which the refrigerant passes to the vaporizing chamber 13.

The expansion valve 36 is of a conventional type in which a valve member 37 is held to its seat by a predetermined pressure of liquid refrigerant received from the condenser coil 12 thereagainst. A spring 38 unseats the valve and permits liquid refrigerant to pass into the discharge pipe 39 intermittently as pressure conditions on opposite sides differentiate to a predetermined degree.

The vaporizing chamber 13 into which the pipe 39 extends and presents its discharge end 40 in an upward direction adjacent the bottom of the chamber, is filled to a level 41 with a mass of the brine-lubricant 26. It will be seen that bubbles 42 of the liquid refrigerant by reason of their relatively low specific gravity, rise through the mass of the brine-lubricant, vaporizing as they rise, and, at the same time setting up a circulation in the mass of brine-lubricant as indicated by the arrows in Figure 2 of the drawings. The completion of the vaporization of the refrigerant takes place at the surface of the brine-lubricant. It will

be seen that the circulation set up in the mass of brine-lubricant by the rise of bubbles therethrough assists in a quick chilling of the mass with a correspondingly rapid refrigeration of the contents of the trays 43.

The gasified refrigerant, with the contained portion of brine lubricant, which is maintained in active circulation throughout the system, is returned to the upper end of the crank case chamber 18, of the compressor through the suction action of the compressor by way of the suction return pipe 44. The liquid brine-lubricant is delivered from the discharge end 45 of the pipe 44 into a sump 46 and finds its way through a channel 47 and a pipe 48 into lubricating relation to the shaft 17, crank pin 49 and also wrist pin 50.

In rising through the return suction pipe 44 the cold gas cools the liquid 51 in which the coil 52, the pipe 35 leading from the condenser coil 12 to the expansion valve 36, is also immersed. The heat interchanger thus provided cools the incoming refrigerant and brine-lubricant.

The heat interchange chamber provides a convenient location for a thermostat 54 arranged to control the operation of the refrigeration system as a whole. The heat interchange liquid 51 is preferably a mass of brine-lubricant or ethylene glycol and the coils of the pipes 35 and 44 are immersed. The base of the thermostat 54 is also immersed in the liquid 51. The heat interchange chamber 55 which is thus provided is located at the top of the refrigerator and is also exposed to atmospheric temperature so that it acts as a magnified temperature difference chamber as compared to the vaporizing chamber proper. The result is that a rise of only two degrees in temperature within the vaporizer chamber will show a ten degree rise of temperature in the heat interchange chamber 55. This differentiation assists the thermostat to maintain the refrigerator at an extremely even temperature because of the relative magnification of temperature differences under which the thermostat operates.

What is claimed is:

1. The method of refrigeration which consists in compressing a volatile refrigerant, condensing the refrigerant, volatilizing the refrigerant in the presence of a non-absorbent lubricating fluid, thereby cooling said fluid, utilizing the cold non-absorbent lubricating fluid as a brine, returning the volatilized refrigerant to the compressor and entraining therewith a predetermined amount of the non-absorbent fluid to lubricate the compressor.

2. The method of refrigeration which consists in compressing a volatile refrigerant, condensing the refrigerant, evaporating

the refrigerant while in cooling proximity to a body of substantially non-absorbent lubricating fluid, thereby cooling the said fluid, utilizing said fluid as a brine, returning the vaporized refrigerant to be recom-
5 pressed in the compressor and drawing in therewith a predetermined volume of the

cold non-absorbent fluid to lubricate the compressor.

Signed at New York, in the county and 10
State of New York, this 10th day of April,
1926.
